DISPLAY HANGER FOR BOOTS

Michael Wahl, Searington, N.Y., assignor to Wahl
Associates, Inc., Long Island City, N.Y.

Filed Mar. 28, 1972, Ser. No. 239,002

Term of patent 14 years

Int. Cl. D6—08

U.S. Cl. D6—252

FIG. 1.

FIG. 2.

FIG. 3.

FIG. 4.

FIG. 5.

FIG. 6.

FIG. 7.

FIG. 1 is an elevational perspective view of a display hanger for boots showing my new design;

FIG. 2 is a front elevational view, on an enlarged scale;

FIG. 3 is a right side view thereof;

FIG. 4 is a rear elevational view thereof;

FIG. 5 is a left side view thereof;

FIG. 6 is a top plan view thereof; and

FIG. 7 is a bottom plan view thereof.

I claim:

The ornamental design for a display hanger for boots, substantially as shown.
